OTTO PETERMANN, OF GROTON, NEW YORK, ASSIGNOR, BY MESNE ASSIGNMENTS, TO CORONA TYPEWRITER COMPANY, INCORPORATED, A CORPORATION OF NEW YORK.

RIBBON MECHANISM FOR TYPE-WRITING MACHINES.

1,121,032.

Specification of Letters Patent.

Patented Dec. 15, 1914.

Application filed June 12, 1909. Serial No. 501,854.

To all whom it may concern:

Be it known that I, OTTO PETERMANN, a citizen of the Republic of Switzerland, and a resident of Groton, county of Tompkins, 5 and State of New York, have invented certain new and useful Improvements in Ribbon Mechanism for Type-Writing Machines, of which the following is a full, clear, and exact description.

10 This invention relates more particularly to the ribbon mechanism of front-strike or visible typewriting machines in which the ribbon has a lengthwise movement and an independent lateral movement from a normal position to cover and uncover the printing point.

15 The primary object of the invention is to provide a simple and efficient machine in which the platen, carriage, escapement and 20 ribbon mechanism may be moved vertically to adapt each type-head or block to have a plurality of characters thereon, and in which the ribbon is given a lateral movement to cover and uncover the printing point, and in 25 such a way that the said ribbon may have different characteristics or a plurality of distinct fields or zones to permit the ribbon to print different colors; and to provide a machine which is so constructed and arranged 30 that the parts referred to may be folded over into compact relation to the keys of the machine to cause the same to occupy less space than when in use and to adapt the machine for transportation or for other purposes.

35 Other objects of the invention are to provide simple means for moving the ribbon lengthwise and laterally each time one of the keys is operated, and to provide a machine in which the parts are very simple and strong in construction and which may be made very light.

40 A further object of the invention is to provide a ribbon mechanism which may be positively driven from the carriage feed, and to provide simple means whereby the ribbon may be caused to move in either direction.

45 With these and other objects in view, the invention will be hereinafter more particularly described with reference to the accompanying drawings, which form a part of this specification, and will then be pointed out in the claims at the end of the description.

In the drawings, Figure 1 is a longitudinal section of one form of machine embodying the invention. Fig. 2 is a detail front elevation of the vertical ribbon guide. Fig. 3 is a detail section, partly in elevation, of 60 the mechanism for raising and lowering the ribbon. Fig. 4 is a detail section, showing a part of the feed mechanism and means for operating the ribbon. Fig. 5 is a rear elevation of the machine. Fig. 6 is an inverted 65 plan view of the carriage support and escapement mechanism. Figs. 7 and 8 are views of parts of the escapement mechanism. Fig. 9 is a plan view of the foldable or shiftable part of the machine including the platen, 70 the ribbon spools and part of the operating mechanism therefor, as well as other features of the machine. Fig. 10 is a detail plan view, partly broken away, of the drum containing the spring for actuating the carriage and to which is held the flexible connection for propelling or drawing forward the carriage; and Fig. 11 is an elevation of 75 one of the ribbon spools, showing in section the spring-actuated drum carrying the 80 flexible connection for imparting a forward movement to the carriage.

The metallic frame 1, Figs. 1 and 5, of the machine is constructed and arranged in any suitable manner, and may consist of side 85 members and an integral back member with an intermediate transverse horizontal bar 2 suitably fastened to the sides of the frame and serving as a brace therefor, and a second transverse bar 2^a at the front of the 90 machine, the whole frame being constructed of sheet metal with rounded edges for the purpose of making the frame light and strong.

The key-levers 3, Fig. 1, may have finger 95 pieces 4, and are each provided intermediate its ends with an upwardly-extending part 5. This part 5 may be integral with the body portion 6, and the whole lever may be stamped from sheet metal or other material for strength and cheapness. The key-levers have their parts substantially U-shaped when viewed from above, so that said levers may be readily and quickly hung or supported from a plurality of transversely-extending bars or members 7 which are located under the transverse bar 8, as shown best in Fig. 1. These levers have their heads 8^a of such width that they may rest 100 against each other in series or banks ac-

cording to the number of bars or members 7. As shown there are three bars 7, and each bar is provided with an upwardly turned or hooked end 9 which is adapted to fit in notches 10 of the key-levers 3 so that said levers will be supported on substantially a knife edge.

Each key-lever 3 is provided with an aperture on its under side in which is adapted to be fastened one end of a spring 11, and the other end of said spring is held to a projecting part 12 stamped or forced from a transverse bar or plate 13 at the lower part of the machine whereby the said levers may be restored to their normal position. The inner ends of the levers are provided with an aperture in which one end of a link 14 is held, and the other end of said link engages a type-bar 15, there being a type-bar 20 for each key-lever. These type-bars are each pivoted at 16, Fig. 1, in a slotted part of a transversely-extending and curved bracket or bar 17 which is held to the rear of the machine frame by means of screws 18 or otherwise. Each type-bar at its outer end is provided with a head or block 19, and each head is provided with a plurality of characters 20, 21 and 22, the former indicating the figures, the intermediate one the upper case, and the third the lower case. These type-bars are each adapted to rest on a felt or other cushioning means 23 which is supported by a transversely-extending and curved plate or bar 24 suitably supported at its ends on the machine frame.

Any suitable platen and means for supporting the same may be employed. As shown the platen 25 is of the usual form and is mounted at its ends to rotate in the frame 40 26 of a carriage 27. The carriage 27 moves along a normally fixed member, bed or support 28, and has a movable member 29 which is opposed to the fixed support or bed 28. The member 29 is provided with grooves 45 lengthwise thereof at its under side, as at 30, and the support 28 with grooves 31 on its upper surface opposed to the grooves 30 so as to form a race-way along the opposite edges of said member, and in the race-ways 50 are arranged balls 32 forming a bearing for the member 27 of the carriage.

The carriage when released by the escapement mechanism, as will be hereinafter described, is moved forward for letter-spacing 55 by a spring 33 arranged in a drum 34, Figs. 10 and 11, one end of which is held to a disk 35 by which the spring may be wound, and the other end to the drum 34, and both the drum and disk are rotatably supported 60 on a shaft 36 over a bracket 37. The disk 35 is provided with finger operating parts 38 and to said disk is pivoted a pawl 39. This pawl 39 is provided with two teeth 40 and 41, the latter of which is on a handle 65 portion 42 of said pawl, and the teeth are

adapted to engage a fixed ratchet wheel 43, by which said disk may be held in an adjusted position and released by a step-by-step movement as desired. A flexible connection 44 is carried by the drum 34 and is held at one end to said drum, and its other end is fastened to the carriage so that when the carriage is released, the tension of the spring will force the same along the bed or support 28.

Various means may be employed for feeding the carriage for letter-spacing and as the escapement mechanism therefor. As shown the carriage is provided with a rack-bar 45 which extends lengthwise of the carriage, 80 and meshing with said rack-bar is a pinion 46, Figs. 1 and 4. This pinion is held to rotate with a shaft 47, which latter is journaled in a bracket located under the carriage bed 28 and projects upward through said bed, and to the lower end of which shaft is held a ratchet wheel 48. This ratchet wheel 48 forms a part of the escapement mechanism and is located above the bracket or plate 49 in which one end of the shaft 47 is 90 journaled. The ratchet wheel 48 is held to rotate with the shaft 47, and adapted to engage the ratchet wheel is an escapement device or lever 50. This lever or device 50 comprises two parts or members 51 and 52, 95 and carried by the member or part 52 are the pawls 53 and 54, the former of which is fixed and the latter pivoted, and said pawls are adapted to engage alternately the teeth of the ratchet wheel 48 to permit said 100 ratchet wheel to rotate with a step-by-step movement. The carriage is moved in one direction by the spring 33, and the movement of the carriage transmits a rotary movement to the ratchet wheel 48 through the rack-bar 45 and pinion 46. The member 52 of the escapement lever is forced in one direction by a spring 55, and said escapement lever is pivoted intermediate the ends thereof at 56 to move horizontally above the 110 bracket 49. By constructing the lever 50 and arranging the pawls as shown, the said pawls are caused to move directly into and out of engagement with the ratchet wheel without a sliding movement, thus materially 115 overcoming the wear and effecting a better alinement in letter-spacing. The pawl 54 is pivoted at 57 and is normally forced against a pin 58 by means of a spring 59, and may be limited in its movement by a screw 60 120 so as to be properly confined in its movement between the end of said screw and said pin. The member 52 is normally forced by a spring 55 in a direction to cause the pawl 54 to engage a tooth of the ratchet wheel 125 48, one end of which spring is fastened to the bracket 49 and the other end to said member, there being a small flat spring 61, Fig. 7, having its free end extending in the path of said ratchet wheel to prevent the 130

same from moving except in one direction. The escapement device or lever 50 is curved or circularly formed to partly encompass the ratchet wheel and at its end opposite the pawl 54 is engaged by the end of the member 51 so as to move the member 52 on its pivot. The member 51 has its end 62 projecting in the path of a vertically movable bar or device 63 to be hereinafter referred to, and as said end 62 is moved it will force the member 52 on its pivot 56. The member 51 is pivoted at 64, Fig. 8, to the bracket 49 and has one end hooked and engaging one end of the member 52 to shift the latter when moved vertically, the normal position of the end 62 of said member 51 being downward. As will be seen when the escapement lever is moved, the ratchet wheel, through the action of the spring 33 which forces the carriage in one direction, will rotate the distance of one tooth at each movement of the escapement device or lever 50.

The ribbon has a lengthwise movement imparted thereto by mechanism coöperating with the escapement mechanism. A bevel or crown gear 65 is fixed on the shaft 47 and is adapted to rotate with the ratchet wheel 48, and formed as a part of the bevel gear is a clutch member 66, the teeth of which engage with the clutch member 67. This clutch member 67 normally rotates with the pinion 46 and is slidably held on the hub of said pinion by a key or otherwise. The clutch member 67 is normally held in engagement with the teeth of the clutch member 66 by a spring 67^a which surrounds the hub of the pinion and has one end abutting against the pinion and its other end against the clutch member 67, said mechanism 67 being released by mechanism not shown when it is desired that the carriage move freely forward along its bed independent of the escapement mechanism and free of any movement of the ribbon mechanism. The ribbon mechanism remains inactive during the backward movement of the carriage owing to the shape of the clutch teeth and the spring 67^a which permits the member 67 to rotate with the pinion in one direction without rotating the clutch member 66 and the crown wheel. A bevel gear or pinion 68, Fig. 5, is secured to one end of each of the horizontally arranged shafts 69, one end of which latter are journaled in brackets 70, located on the support or carriage bed, and the other ends are journaled in brackets 70, Fig. 6. These shafts 69 are angularly arranged with respect to each other and to the longitudinal plane of the carriage, and said shafts are provided with worms 71 which mesh with the gears 72. These gears 72 are each held to one of the shafts 36, Figs. 10 and 11, and are adapted to rotate said shafts when the worms 71 are rotated. At the upper end of each of the shafts 36

is a ribbon spool 73, and arranged upon each of said shafts 36 is a thumb nut 74 which is adapted to clamp either of the spools so as to be held to its shaft, or to rotate independently, so that by 70 tightening one thumb nut and releasing the other the ribbon may be wound from one spool to the other, for in one case the spool will rotate with the shaft while the other spool will be free to rotate independently of said shaft. A guide 75 is secured to a bracket 76 which projects from the bracket 37, and said guide 75 is provided with a slot one part of which is open, as at 76^a, for the insertion of the ribbon and 80 through which the ribbon may be passed as it is wound from one spool to the other. The ribbon is made to extend inward adjacent to the platen 25. At this point a vertically movable ribbon guide, member or 85 support 77, Figs. 1 to 3, is provided, and this guide has two guide members or parts 78 and 79 located on opposite sides of the printing point of the type and angularly arranged with respect to the vertical plane 90 of said guide. Each guide member of the guide is slotted at 79^a to receive and hold the ribbon, said slots being open for a part of their length so that the same may be readily inserted in the slots or removed from 95 said slots.

To reciprocate the ribbon guide or guide support 77 laterally as each key is operated to adapt the machine to use a polychrome ribbon, and to adapt the ribbon to move out 100 of the way after the printing has been effected in order to allow the writing to be visible, the guide 77 is supported to move vertically on a bracket or member 80 projecting outward from the carriage bed or 105 support 28. The bracket 80 is slotted, as at 81, at the upper end thereof, and is provided with two outwardly-projecting parts 82 which form a substantially V-shaped opening for the type-heads or blocks to properly 110 guide each head at the printing point for the purpose of securing perfect register. The guide 77 is slotted at its upper end and is provided with two projections 83 on opposite sides thereof which engage the edges 115 of the bracket 80 and is adapted to slide vertically thereon. A spring 84, Fig. 2, is secured at one end to the bracket 80, and at its other end to the guide 77, and said spring normally forces the guide downward. Secured to the guide and at the rear thereof is a member 85 which is pivoted at 86 to the guide and has its lower end provided with a projecting part 87 so as to make the same L-shaped, and with a projecting engaging part 88. The pivoted member 85 is arranged in the path of the vertically movable bar 63, which also operates the escapement lever 50, and when the member 85 of the ribbon and guide is in the po- 125 130

sition shown in full lines in Fig. 2, the said bar 63 will engage the projecting part 88 and will move the ribbon a part of its extreme vertical throw so that the type may 5 print from the upper part of the ribbon, and when the member is moved to the position shown in dotted lines, the bar 63 will engage the lower end 87 of the member 85 and will force the ribbon guide to its extreme throw to print from the lower part 10 of the ribbon, the said movement of the member 85 being effected very easily by the operator simply moving the part 87 with his finger. By this means a simple and 15 efficient mechanism is provided for reciprocating or vibrating the ribbon for visible writing and for adapting the ribbon to have more than one color thereon, at the same time causing the ribbon to return to the 20 same normal position.

The ribbon mechanism, platen, and carriage may be elevated and may be adapted to be folded over above the keys to make the machine more compact in a shifted or 25 folded position than when in use, and said platen may be operated for line spacing in any desired way. The bracket 89 is fixed to a transverse rod 89^a and is arranged to extend under the vertically movable bar 63, 30 and said bar is normally forced into engagement with the bracket by means of a spring 90. This bar 63 is provided at its lower end with a plurality of teeth 91, which form abutments and are adapted to be engaged 35 to a tooth 92 carried by the lower end 93 of an angular lever or arm 94, the said arm being pivoted at 95 to the transverse bar 8 which supports the key-levers. The part 93 is notched at 96, and engaging the notch is 40 a universal bar 97 which extends transversely of the machine across and over each of the key-levers and is pivotally held to swing upward and downward. As will be seen when any of the key-levers are de- 45 pressed, the universal bar 97 will be operated and this will operate the arm 94, and by reason of the tooth 92 will operate the vertically movable bar 63 to vibrate the ribbon and to simultaneously operate the es- 50 capement lever 51. By reason of the teeth in the lower end of the escapement bar 63, the tooth 92 of the arm 94 will engage the bar 63 no matter what position the car- 55 riage may be in, as the said bar is elevated by the shift keys through the bracket 89. The universal bar 97 is also operated by the spacing levers 98 which have the usual finger bar 99, and are each provided with upwardly-projecting hooked portions 100 60 which engage the transverse bar 7 and pivotally support said spacing levers, thus the ribbon is properly positioned whatever key or device is operated to move the carriage or the platen.

65 Two shift levers 101 and 102 are provided

for the purpose of elevating the carriage bed, carriage, ribbon mechanism, and the parts mounted upon and movable with the carriage bed to different vertical positions to adapt each type-head or block to have 70 three characters. The lever 102 is rigidly held to a transversely-extending rod 89^a intermediate its ends and at its inner end is connected to a vertically movable slide 103, there being a slide at each rear end of the 75 machine. The slides are connected to move in unison and are suitably guided in the machine frame. Each slide is substantially L-shaped in form and pivoted at 104 to the outer ends of said slides are the arms 80 or bars 105 which are located on opposite sides of the machine. The bars or arms 105 support the carriage bed, carriage and ribbon mechanism and normally move with the slides when in working position, and 85 said bed, carriage and ribbon mechanism are adapted to be shifted or folded forward over the keys to cause the machine to be more compact and to occupy less space in such folded position than when in use. The 90 shift lever 101 is held to move independent of the transverse rod 89^a and is connected by a screw-and-slot connection, as at 106, to the shift lever 102 whereby the said lever 101 may have a limited movement inde- 95 pendent of the lever 102, but on further movement, will, through the lever 102, ele- 100 vate the slides and support with the parts and mechanism mounted thereon to a degree differing in extent from that of the lever 102, said lever 101 co-operating with mech- 105 aism, not shown, to cause the carriage and support to have such movement, said platen shift mechanism being clearly shown and claimed in my pending application Sr. No. 501,850, filed July 12, 1909.

While I show and describe certain fea- 110 tures of the invention other than the ribbon mechanism proper and the parts co-operating therewith, such features are not specifically claimed herein as they form subject matter of separate applications filed by me under the titles of escapement mechanism, Sr. No. 506,442, filed July 7, 1909; keyboards, Sr. No. 501,853, filed June 12, 1909; and bar mechanism, Sr. No. 501,849, filed June 12, 115 1909, other features being covered in other pending applications.

From the foregoing it will be seen that 120 simple and efficient means are provided whereby a ribbon may be moved in either direction, and in which a plurality of colors may be carried by the ribbon to adapt the same to produce writing of different colors; that simple means are provided for shifting 125 the position of the ribbon by the movement of the keys; that said ribbon may have its mechanism positively driven by the feed that operates to move the carriage; that simple and efficient supporting means for 130

holding the ribbon at the printing point is provided and which is so constructed as to be readily moved to different distances according to which type of the type-heads 5 are being used; and that said mechanism is adapted to be moved vertically with the carriage and to be folded with the carriage to make the machine very compact when not in its normal working position.

10 Having thus described my invention, I claim as new and desire to secure by Letters Patent:-

1. In a typewriting machine, the combination of a movable carriage, an escapement 15 mechanism connected with the carriage and having a lever forming a part thereof, a vertically reciprocating ribbon guide disconnected from and having a part in close 20 relation to the escapement lever, and means for conjointly and directly operating the lever of the escapement mechanism and ribbon guide.

2. In a typewriting machine, the combination of a movable carriage, an escapement 25 mechanism connected with the carriage and having a lever forming a part thereof, a vertically reciprocating ribbon guide disconnected from and having a part thereof in close relation to the escapement 30 lever, and vertically movable means for conjointly and independently operating the lever of the escapement mechanism and vibrating the ribbon.

3. In a typewriting machine, the combination 35 with a movable carriage, of a rotary escapement mechanism connected with said movable carriage and having a rotary gear wheel and a lever, rotary spools on which the ends of a ribbon may be wound, a worm 40 gear on the shaft of each of said spools, horizontally arranged rotary shafts, each having a worm on each shaft constantly in mesh with the gear on one of the spool shafts, a gear held to the opposite end of 45 each horizontally arranged shaft and constantly in mesh with the first-mentioned gear, and means for operating the lever.

4. In a typewriting machine, the combination 50 with a movable carriage, of an escapement mechanism connected with said movable carriage and having a rotary crown wheel and a lever, rotary ribbon spools, a gear on the shaft of each of said rotary spools, angularly arranged rotary shafts 55 each having at one end a worm constantly in mesh with the gear on the ribbon shaft and at the other end a gear each constantly in mesh with said crown wheel, and means for operating the escapement mechanism.

60 5. In a typewriting machine, the combination 65 with a movable carriage, of an escapement mechanism connected with said movable carriage and having a rotary crown wheel, rotary ribbon spools, a worm gear on the shaft of each of said rotary spools,

angularly arranged shafts a worm held to one end of each shaft and constantly in mesh with the gear on the ribbon spool shaft, a bevel gear held at the other end of each shaft and constantly in mesh with said 70 crown wheel, and means for operating the escapement mechanism.

6. In a typewriting machine, the combination with a movable carriage for supporting the platen, of an escapement mechanism 75 connected with the movable carriage, ribbon spools, vertically reciprocating mechanism for vibrating the ribbon, said escapement mechanism having a laterally projecting lever disconnected from and having a part 80 thereof located adjacent to the ribbon vibrating mechanism, key-operated levers, and means operated by said levers and simultaneously acting directly upon said ribbon guide and the lever of the escapement 85 mechanism.

7. In a typewriting machine, the combination with a movable carriage for supporting the platen, of an escapement mechanism connected with the movable carriage, ribbon spools, a vertically reciprocating guide 90 for vibrating the ribbon, said escapement mechanism having a laterally projecting lever disconnected from and having a part thereof located adjacent to the ribbon vibrating mechanism, key-operated levers, and a vertically movable element operated by the key-operated levers and acting directly upon said ribbon guide and the lever 95 of the escapement mechanism.

8. In a typewriting machine, the combination with a support, of a carriage mounted on said support, feed mechanism for the carriage, ribbon mechanism mounted on the support and operated from the feed mechanism, a vibratory ribbon guide, a vertically reciprocatory bar adapted to directly engage a part of and simultaneously operate the feed mechanism and the ribbon guide, a universal bar, and connections between 100 the universal bar and the reciprocatory bar whereby on each movement of said universal bar the reciprocatory bar will operate to vibrate the ribbon.

9. In a typewriting machine, the combination with a support, of a carriage mounted on said support, feed mechanism for the carriage, ribbon mechanism mounted on the support and operated from the feed mechanism, an independent vibratory ribbon 115 guide, a vertically reciprocatory bar adapted to simultaneously operate the feed mechanism and the ribbon guide independently of each other, a universal bar, and connections between the universal bar and the reciprocatory bar whereby on each movement of said universal bar the reciprocatory bar 120 will operate to vibrate the ribbon.

10. In a typewriting machine, the combination of a platen, a ribbon, means for mov- 130

- ing the ribbon adjacent to the platen, a reciprocatory guide engaging the ribbon for vibrating the same, a reciprocatory bar for engaging the ribbon guide and provided with a plurality of teeth, a universal bar, a pivotally held arm engaged by the universal bar and having a tooth adapted to engage the teeth of the reciprocatory bar to operate the latter when the universal bar is operated.
11. In a typewriting machine, the combination of a platen, means for moving the ribbon lengthwise adjacent to the platen, a reciprocatory guide engaging the ribbon for vibrating the same laterally to cover and uncover the printing point, a reciprocatory bar for engaging the ribbon guide and provided with a plurality of teeth, a universal bar, a pivotally held arm engaged by the universal bar and having means adapted to engage the teeth of the reciprocatory bar to operate the latter when the universal bar is operated.
12. In a typewriting machine, the combination with a carriage, of escapement mechanism including a lever, ribbon mechanism including a shiftable member, key-levers, together with a vertically movable bar adapted to simultaneously engage the lever and said member to operate the escapement mechanism and to vibrate the ribbon.
13. In a typewriting machine, the combination of a carriage, a platen mounted on the carriage, escapement mechanism, ribbon mechanism including a laterally movable element, key-levers, together with a vertically movable bar adapted to engage said element and a part of the escapement mechanism to operate said latter mechanism and to vibrate the ribbon.
14. In a typewriting machine, the combination with a carriage movable into compact relation to another part of the machine to occupy less space than when in use, of escapement mechanism, ribbon mechanism including a laterally movable member and carried with the carriage in its compact movement, key-operated levers, together with a device co-operating with the levers and adapted to engage said element and a part of the escapement mechanism to simultaneously operate said latter mechanism and move the ribbon to cover the printing point.
15. In a typewriting machine, the combination of a carriage, escapement mechanism, ribbon mechanism including a reciprocatory guide, key-levers, together with a vertically movable and independent bar directly engaging said guide and a part of the escapement mechanism to simultaneously operate said escapement mechanism and move the ribbon laterally to cover the printing point.
16. In a typewriting machine, the combination with a carriage and a platen mount-
- ed on said carriage, of an escapement mechanism including a lever, ribbon vibrating mechanism including a vertically movable element, key-levers, and means operatively connected to the key-levers for directly operating the escapement lever and the vertically movable element of the ribbon mechanism, said means being independent of and separable from the escapement lever and the element of the ribbon mechanism.
17. In a typewriting machine, the combination with a carriage and a platen mounted on said carriage, of an escapement mechanism, ribbon vibrating mechanism including a vertically movable element, means co-operating with the escapement mechanism to move the ribbon lengthwise, key-levers, and means operatively connected to the key-levers for directly and simultaneously operating the escapement and the vertically movable element of the ribbon mechanism, said means being independent of and separable from said mechanisms.
18. In a typewriting machine, the combination with a carriage and a platen mounted on said carriage and movable forward therewith into compact relation to another part of the machine, of an escapement mechanism, ribbon vibrating mechanism including a two-part member partaking of the compact movement of the carriage, key-levers, and a vertically movable device operatively connected with the key-levers and separable from the ribbon and escapement mechanisms for simultaneously operating said escapement mechanism and the vertically movable element of the ribbon mechanism.
19. In a typewriting machine, the combination with a support, of a carriage mounted to move along said support, a platen held in the carriage and movable with the carriage into compact relation to another part of the machine, ribbon vibratory mechanism mounted upon the support and partaking of the compact movement of the carriage, said ribbon mechanism including a vertically movable element, escapement mechanism, means operatively connected with the escapement mechanism for moving the ribbon lengthwise, said mechanism also partaking of the compact movement of the carriage and platen, key-operated levers, and a vertically movable bar connected with said levers and adapted to simultaneously operate a part of the escapement mechanism and the ribbon mechanism.
20. In a typewriting machine, the combination with a support, of a carriage mounted to move along said support, a platen held in the carriage and foldable forward with the carriage into compact relation to another part of the machine, ribbon vibratory mechanism mounted upon the support and foldable with the carriage, escapement

mechanism, means operatively connected with the escapement mechanism for moving the ribbon lengthwise, said mechanism being foldable with the carriage and platen in its compact movement, key-operated levers, and a movable element operatively connected to said levers and adapted to simultaneously move a part of the escapement mechanism and the ribbon mechanism.

21. In a typewriting machine, the combination with a support, of a carriage mounted to move along said support, a platen held in the carriage and movable with the carriage into overhanging relation to the keys, ribbon vibratory mechanism mounted upon the support and movable with the carriage, said ribbon mechanism including a vertically reciprocating element, escapement mechanism, means operatively connected to the escapement mechanism for moving the ribbon lengthwise, said mechanism being movable with the carriage and platen in its compact movement, key-levers, and a vertically movable bar connected to said key-levers and adapted to simultaneously operate a part of the escapement mechanism and the ribbon mechanism.

22. In a typewriting machine, the combination of a support, a carriage mounted to move along said support, a platen held in the carriage and foldable forward with the carriage into overhanging relation to another part of the machine to occupy less space than when in use, ribbon vibratory mechanism mounted upon the support and foldable with the carriage, escapement mechanism, means for moving the ribbon lengthwise, said mechanism partaking of the compact movement of the carriage and platen, key-levers, and a vertically movable bar operatively connected to said key-levers and adapted to simultaneously operate a part of the escapement mechanism and the ribbon mechanism.

23. In a typewriting machine, the combination of a support, a carriage mounted to move along said support, a platen held in the carriage and movable forward with the carriage into compact relation to another part of the machine, ribbon vibratory mechanism mounted upon the support and partaking of the forward movement of the carriage, escapement mechanism, key-levers, and a vertically movable bar connected to said key-levers and adapted to simultaneously operate a part of the escapement mechanism and the ribbon mechanism.

24. In a typewriting machine, the combination of a support, a carriage mounted to move along said support, a platen held in the carriage and foldable with the carriage into overhanging relation to the keys, ribbon vibratory mechanism mounted upon the support and foldable with the carriage, escapement mechanism, key-levers, and a verti-

cally movable bar connected to said key-levers and adapted to simultaneously and independently operate a part of the escapement mechanism and the ribbon mechanism.

25. In a typewriting machine, the combination of a carriage, a platen mounted on the carriage, escapement mechanism, ribbon vibratory mechanism entirely independent of the escapement mechanism, key-operated levers, together with a movable element co-operating with said levers and simultaneously and independently operating a part of both the escapement mechanism and the ribbon mechanism.

26. In a typewriting machine, the combination of a carriage, a platen mounted on the carriage, escapement mechanism, ribbon mechanism disconnected from and having a part located adjacent to a part of the escapement mechanism, key-operated levers, together with a vertically movable and reciprocating element co-operating with said levers and simultaneously operating a part of both the escapement mechanism and the ribbon mechanism.

27. In a typewriting machine, the combination of a carriage, a platen mounted on the carriage and foldable forward therewith over the keys to occupy less space than when in use, ribbon mechanism foldable with the carriage, key-operated levers, together with a vertically movable element separable from the ribbon mechanism and co-operating with said levers and adapted to operate a part of the ribbon mechanism.

28. In a typewriting machine, the combination of a carriage, a platen mounted on the carriage and movable therewith into compact relation to another part of the machine to occupy less space than when in use, ribbon mechanism partaking of the compact movement of the carriage, key-operated levers, together with a reciprocating element co-operating with said levers and operating a part of the ribbon mechanism to cover the printing point.

29. In a typewriting machine, the combination of a carriage, a support for said carriage, a platen mounted on the carriage and movable with the carriage into compact relation to another part of the machine, ribbon vibratory mechanism partaking of the compact movement of the carriage, mechanism for moving the ribbon lengthwise, also partaking of the compact movement, escapement mechanism serving as a means to operate the mechanism for moving the ribbon lengthwise, key-operated levers, and a vertically movable element co-operating with said levers and adapted to simultaneously operate the ribbon mechanisms and the escapement mechanism as each key-operated lever is depressed.

30. In a typewriting machine, the combination of a carriage, a support for said

- carriage, a platen mounted on the carriage and movable forward with the carriage into compact relation to another part of the machine, ribbon vibrating mechanism partaking of the compact movement of the carriage, mechanism for moving the ribbon lengthwise, also partaking of the compact movement of the carriage, escapement mechanism, key-operated levers, and a vertically movable and reciprocatory bar independent of and separable from the ribbon mechanism and coöperating with said levers and adapted to operate the ribbon vibrating mechanism to cover the printing point. 70
- 15 31. In a typewriting machine, the combination of a carriage, a support for said carriage, a platen mounted on the carriage and movable with the carriage into compact relation to another part of the machine, ribbon vibrating mechanism movable with the carriage, mechanism for moving the ribbon lengthwise partaking of the compact movement of the carriage, key-operated levers, and a vertically movable element separable 75
- 20 from the ribbon mechanism and remaining in coöperation with said levers and adapted to operate a part of the ribbon vibratory mechanism to cause the ribbon to cover and uncover the printing point. 80
- 25 32. In a typewriting machine, the combination of a carriage, a support for said carriage, a platen mounted on the carriage and movable forward with the carriage and support into compact relation to another 85
- 30 part of the machine to occupy less space than when in use, ribbon vibrating mechanism partaking of the compact movement of the carriage, key-operated levers, and a reciprocatory element separable from the 90
- 35 ribbon mechanism and remaining in coöperation with said levers and adapted to operate a part of the ribbon vibratory mechanisms to cause the ribbon to cover and uncover the printing point. 95
- 40 33. In a typewriting machine, the combination of a carriage, a vertically movable support for said carriage, a platen mounted on the carriage and movable forward with the carriage and support into compact relation to another part of the machine to occupy less space than when in use, ribbon vibrating mechanism partaking of the compact movement of the carriage and support, mechanism for moving the ribbon lengthwise, key-operated levers, and a vertically movable bar movable vertically with the platen and coöperating with said levers and having a movement independent of the vertical shift movement of said bar and adapted 100
- 45 to operate the ribbon vibrating mechanism. 105
- 50 34. In a typewriting machine, the combination of a carriage, a support for said carriage, a platen mounted on the carriage and movable with the carriage into compact relation to another part of the machine to 110
- 55 occupy less space than when in use, platen shift mechanism for moving the carriage and platen vertically, ribbon vibrating mechanism partaking of the compact movement of the carriage, key-operated levers, means for moving the ribbon lengthwise, and a bar forming a part of the ribbon mechanism having a vertical movement through the platen shift mechanism and maintained in a fixed relative position to the platen, said bar coöperating with said levers and having a movement thereby independent of its movement through the platen shift mechanism to operate the vibrating mechanism for moving the ribbon laterally. 115
- 60 35. In a typewriting machine, the combination of a carriage, a support for said carriage, a platen mounted on the carriage, platen shift mechanism, ribbon vibratory mechanism, key-operated levers, and a vertically movable bar having a vertical movement through the platen shift mechanism and maintained in a fixed relative position to the platen, said bar coöperating with said levers and having a movement thereby independent of its movement through the platen shift mechanism to operate by impact the rest of the ribbon vibrating mechanism. 120
- 65 36. In a typewriting machine, the combination of a carriage, a support for said carriage, a platen mounted on the carriage, platen shift mechanism for moving the carriage and platen vertically, ribbon vibrating mechanism for moving the ribbon to cover and uncover the printing point, and a reciprocatory element having a movement through the platen shift mechanism and maintained in a fixed relative position to the platen, and key-operated levers, said element coöperating with said levers and having a movement thereby independent of its movement through the platen shift mechanism to operate by impact the rest of the ribbon vibrating mechanism. 125
- 70 37. In a typewriting machine, the combination of a support, a carriage mounted to move along said support, a platen held to rotate with the carriage, means for imparting a lengthwise movement to the ribbon, a vertically movable ribbon element adapted to engage the ribbon and to move the same laterally of the platen to cover and uncover the printing point and adapted always to return to the same normal position below the printing point, a bracket along which said ribbon element is adapted to slide, a member pivotally held to the ribbon element and having two engaging parts arranged one above the other, a spring normally forcing the ribbon element downward, key-operated levers, and a vertically reciprocatory bar coöperating with said key-operated levers and adapted to engage the engaging parts of said member to vary the lateral throw thereof. 130

38. In a typewriting machine, the combination with a support, of a carriage mounted to move along said support, means for moving the support vertically, a platen held to rotate with the carriage, means for moving a ribbon lengthwise of the platen, a vertically movable element adapted to engage the ribbon and to move the same laterally of the platen to cover and uncover the printing point, a bracket along which said element is adapted to slide, a member pivotally held to the element and having a plurality of engaging parts arranged one above the other, a spring normally forcing the ribbon element downward, key-operated levers, and a vertically reciprocating bar coöperating with the key-operated levers and adapted to engage the engaging parts of said member to vary the lateral throw thereof.

39. In a typewriting machine, the combination with a support, of a carriage mounted to move along said support, a platen held to rotate with the carriage, means for moving the platen, carriage and support vertically, means for moving a ribbon lengthwise, a vertically movable element adapted to engage the ribbon and to move the same laterally of the platen to cover and uncover the printing point, said element being movable vertically with the carriage, a bracket along which said element is adapted to slide, a member pivotally held to the element and having a plurality of engaging parts arranged one above the other, a spring normally forcing the ribbon element downward, key-operated levers, and a vertically reciprocating bar coöperating with the key-operated levers and adapted to engage the engaging parts of said member to vary the lateral throw thereof.

40. In a typewriting machine, the combination with a support, of a carriage mounted to move along said support, a platen held to rotate with the carriage, means for moving a ribbon lengthwise of the platen, a vertically movable element adapted to engage the ribbon and to move the same laterally of the platen to cover and uncover the printing point, a bracket along which said element is adapted to slide, a member pivotally held to the element and having a plurality of engaging parts arranged one above the other, a spring normally forcing the ribbon element downward, means for moving the carriage, support and ribbon element vertically, key-operated levers, and a vertically reciprocating bar shiftable with the platen and carriage and coöperating with the key-operated levers and adapted to engage the engaging parts of said member to vary the lateral throw thereof independent of the shifting movement.

41. In a typewriting machine, the combination with a support, of a carriage mount-

ed to move along said support, a platen held to rotate with the carriage, and foldable with the carriage forward into compact relation to another part of the machine to occupy less space than when in use, means for moving a ribbon lengthwise foldable with the carriage, a vertically reciprocating element adapted to engage the ribbon and to move the same laterally of the platen to cover and uncover the printing point, and adapted always to return to a normal position below the printing point, said element partaking of the folding movement of the carriage, a bracket along which said element is adapted to slide, a lever pivotally held to the element and having a plurality of engaging parts, key-operated levers, and a vertically movable bar coöperating with the key-operated levers and adapted to engage the engaging parts of the ribbon element to vary the lateral throw thereof.

42. In a typewriting machine, the combination with a support, of a carriage mounted to move along said support, a platen held to rotate with the carriage and foldable with the platen into compact relation to another part of the machine, means for moving a ribbon lengthwise and partaking of the folding movement, a vertically movable element adapted to engage the ribbon and to move the same laterally of the platen to cover and uncover the printing point, said element also partaking of the folding movement, a bracket along which said element is adapted to slide, key-operated levers, and a vertically movable element coöperating with the key-operated levers and adapted to engage the ribbon element to vary the lateral throw thereof.

43. In a typewriting machine, the combination with a support, of a carriage adapted to move along said support, means for imparting a lengthwise movement to a ribbon, ribbon vibrating mechanism for imparting a lateral movement to the ribbon to cover and uncover the printing point, a vertically movable bar having spaced engaging parts, means for elevating the carriage and ribbon mechanisms, a spring normally forcing said bar downward, key-operated levers, a universal bar adapted to be operated by said levers as the same are depressed, an arm having a hooked end adapted to be engaged by the universal bar and having a hooked part adapted to engage the spaced engaging parts of the vertically movable ribbon operating bar in whatever position the latter may be in to move the ribbon to cover the printing point.

44. In a typewriting machine, the combination with a support, of a carriage adapted to move along said support, means for imparting a lengthwise movement to a ribbon, ribbon vibrating mechanism for imparting

- a lateral movement to the ribbon to cover and uncover the printing point, a vertically movable bar having spaced engaging parts, means for elevating the carriage and ribbon mechanisms, key-operated levers, a universal bar adapted to be operated by said levers as the same are depressed, an arm having a part adapted to be engaged by the universal bar and having also a part adapted to engage the spaced parts of the vertically movable ribbon operating bar in whatever position the latter may be in to move the ribbon to cover the printing point.
45. In a typewriting machine, the combination with a support, of a carriage adapted to move along said support, means for imparting a lengthwise movement to a ribbon, ribbon vibrating mechanism for imparting a lateral movement to the ribbon to cover and uncover the printing point, a vertically movable bar having spaced engaging parts, key-operated levers, and means coöperating with said levers to operate the bar.
46. In a typewriting machine, the combination with a support, of a carriage adapted to move along said support, means for imparting a lengthwise movement to a ribbon, ribbon vibrating mechanism for imparting a lateral movement to the ribbon to cover and uncover the printing point, a vertically movable bar having spaced engaging parts, means for elevating the carriage and ribbon mechanisms, key-operated levers, a universal bar adapted to be operated by said levers as the same are depressed, and means operated by said universal bar adapted to move said vertically movable bar in whatever position the latter may be in to move the ribbon to cover the printing point.
47. In a typewriting machine, the combination of a carriage bed, a support therefor, a carriage adapted to move along said bed, a platen mounted in the carriage and movable with the bed and carriage into compact relation to another part of the machine, mechanism for moving a ribbon lengthwise thereof, ribbon vibrating mechanism adapted to move the ribbon laterally to cover and uncover the printing point, all of which partake of the compact movement of the carriage and bed, key-operated levers, a vertically movable bar adapted to assume different positions, and means operatively connected to the key-operated levers whereby said bar may be moved to operate the ribbon vibrating mechanism.
48. In a typewriting machine, the combination with a carriage bed, a support therefor, a carriage adapted to move along said bed, a platen mounted in the carriage, mechanism for moving a ribbon lengthwise thereof, ribbon vibrating mechanism adapted to move the ribbon laterally to cover and uncover the printing point, key-operated levers, a vertically movable bar adapted to

assume different positions, and means operatively connected to the key-operated levers whereby said bar may be moved to operate the ribbon vibrating mechanism.

49. In a typewriting machine, the combination of a carriage bed, a support therefor, a carriage adapted to move along said bed, a platen mounted in the carriage and movable forward with the bed and carriage into compact relation to the keys of the machine, mechanism for moving a ribbon lengthwise thereof, ribbon vibrating mechanism adapted to move the ribbon laterally to cover and uncover the printing point, all of which partake of the forward movement of the carriage and bed, key-operated levers, a vertically movable bar adapted to assume different positions, and means operatively connected to the key-operated levers whereby said bar may be moved to operate the ribbon vibrating mechanism.

50. In a typewriting machine, the combination with a carriage support, of a carriage adapted to move along said support, a platen mounted in the carriage, escapement mechanism including a rotary shaft, ribbon spools mounted on the support and located on opposite sides of the machine, a shaft on which the spools are mounted and adapted to be held to said shaft or to be released therefrom, a worm gear mounted on each shaft, worms meshing with said worm gears, angularly arranged shafts to which the worms are secured, a crown wheel mounted on the shaft, a clutch mechanism coöperating with said crown wheel, means whereby the clutch mechanism may be released to disengage the crown wheel from coöperation with the escapement mechanism, gears arranged on the shafts to constantly mesh with the crown wheel whereby either one of the ribbon spools may be rotated to move the ribbon lengthwise thereof, key-levers, and means coöperating with the key-levers for operating the escapement mechanism.

51. In a typewriting machine, the combination with a carriage support, of a carriage adapted to move along said support, a platen mounted in the carriage, escapement mechanism including a rotary shaft, ribbon spools mounted on the support and located on opposite sides of the machine, a shaft on which the spools are mounted and adapted to be held to said shaft or to be released therefrom, a worm gear mounted on each shaft, worms meshing with said worm gears, horizontal and angularly arranged shafts to which the worms are secured, a crown wheel mounted on the shaft, a clutch mechanism coöperating with said crown wheel, means whereby the clutch mechanism may be released to disengage the crown wheel from coöperation with the escapement mechanism, gears arranged on the horizontal shafts to

mesh with the crown wheel whereby either one of the ribbon spools may be rotated to move the ribbon lengthwise thereof, key-levers, and means coöperating with the key-levers for operating the escapement mechanism.

52. In a typewriting machine, the combination with a support, of a carriage adapted to move along said support, escapement mechanism, spools located at opposite sides of the machine about which the ribbon is adapted to pass, shafts to which said spools

are adapted to be held, means for locking or releasing the spool on either of said shafts, a spring held drum arranged upon one of the shafts, and means connecting said drum to the carriage whereby the latter may be propelled along its support. 15

This specification signed and witnessed this 4th day of June A. D. 1909.
